(57) **CLAIM**

The ornamental design for a back cover for display screens with power distribution, as shown and described.

DESCRIPTION

1. Back cover for display screens with power distribution

1.1 : Perspective

1.2 : Front

1.3 : Back

1.4 : Left

1.5 : Right

1.6 : Top

1.7 : Bottom

In the center of the claimed design, there is a power distribution unit that distributes power to multiple displays; the broken lines indicate portions of the article that form no part of the claimed design.
